UNITED STATES PATENT OFFICE.

RAYMOND FISHER, OF PHILADELPHIA, PENNSYLVANIA.

SINKER MECHANISM.

1,281,933.

Specification of Letters Patent. Patented Oct. 15, 1918.

Application filed October 23, 1916. Serial No. 127,213.

To all whom it may concern:

Be it known that I, RAYMOND FISHER, a citizen of the United States, residing at Philadelphia, in the State of Pennsylvania, 5 have invented a certain new and useful Improvement in Sinker Mechanism, whereof the following is a specification, reference being had to the accompanying drawing.

My invention may be employed with particular advantage in an automatic knitting machine adapted for using fine yarns, and particularly artificial silk threads. All such yarns must be knotted at intervals, and each knot is apt to cause a defect in the fabric by 10 catching in a sinker and breaking the thread. Of course, the more frangible the yarn, the more frequently it must be knotted and, consequently, a knot required to connect the end of one bobbin thread with another may occasion a succession of breaks in the fabric such 15 that an entire stocking length is wasted. Therefore, it is the object of my invention to so construct and arrange sinker mechanism that it is capable of performing its ordinary function of casting the loops from the needles by positive movement of each sinker at 20 the proper time, but nevertheless capable of permitting any sinker to yield, radially outwardly, at the proper instant to permit the 25 passage of a knot through the throat of the sinker, without breaking the thread in which the knot is formed, no matter how fine and frangible such thread may be. As herein-after described, such operation is effected by 30 including in the sinker mechanism, cams to actuate the sinkers, which are of substantially the same shape as the cams which are 35 ordinarily rigidly mounted in the sinker ring for that purpose, but pivotally securing such cams at one end, leaving the other 40 end capable of movement radially with respect to the circle of needles; limiting the inward movement of said cams by stop devices which are adjustable to precisely predetermine 45 the extent to which each sinker may be moved inwardly by each cam; and providing a spring which normally holds each cam against the stop devices so that, during ordinary operation of the knitting machine, in 50 which my invention is embodied, the sinkers act in the usual manner, as if the cams were rigidly mounted in the sinker ring. However, the construction and arrangement is such that each cam may yield, outwardly, so 55 that a sinker which is encountered by a knot will cause the cam to thus yield to permit the

passage of the knot. The pressure necessary to cause such yielding movement of the sinker and its actuating cam may be precisely predetermined by adjustment of the 60 pressure of the spring with which the cam is provided.

My invention includes the various novel features of construction and arrangement hereinafter more definitely specified. 65

In said drawing: Figure I is a plan view of a sinker ring, such as is ordinarily employed in what is known as a "Banner" automatic knitting machine, but modified to embody my invention. 70

Fig. II is an elevation of the edge of said ring at the lower portion of Fig. I.

Fig. III is a fragmentary elevation of a portion of the edge of said ring at the left of Fig. I. 75

Fig. IV is a fragmentary sectional view of said ring, taken on the line IV IV in Fig. I, and including an ordinary needle in the position in which the sinker mechanism casts a loop therefrom. 80

Fig. V is a fragmentary sectional view of said ring, taken on the line V V in Fig. I.

Fig. VI is a perspective view of one of the sinker cams indicated in dotted lines in Fig. I. 85

In said figures; the sinker ring 1 is provided with the usual bracket 2 having the opposite abutment screws 3 in threaded engagement therewith and provided with the jam nuts 5 whereby the ring is held in 90 proper relation with a knitting machine. Said ring has the ordinary, double pointed, stationary cam 7 whereby a circular series of sinkers 8 are thrust radially outward (by engagement with their butts 9,) with respect 95 to a circular series of needles 10, at the proper time, and also has the ordinary stationary flange 11 limiting the outward movement of said sinkers 8, except at the region of said ring occupied by the cams. 100 Said ring is also provided with two single pointed cams 13 respectively opposed to the points of said stationary cam 7, and of the same shape as the cams which are ordinarily 105 rigidly secured in such a ring to thrust said sinkers inwardly by engagement with their butts 9 aforesaid. However, said cams 13 are respectively pivotally secured in said ring 1 by screws 14 which, as shown in Fig. V have smoothly cylindrical shanks extending in 110 said ring but are rigidly secured in the respective cams by their threads. Said cams

13 are fitted to oscillate, upon their pivots 14, in the slot 16 which extends circumferentially in said ring 1, as shown in Figs. II, IV and V, and the movement of said cams is 5 limited by screws 18 which are respectively rigidly secured therein by their threads, as indicated in Fig. IV. Said screws 18 extend through respective holes 19 in said ring 1, which are larger than the shanks of said 10 screws, as indicated in Fig. IV, so as to permit oscillation of said cams 13; and the single spiral spring 21 extends in said slot 16 in resilient engagement with each of said cams 13, tending to thrust them inwardly; 15 said spring being stretched between terminal hooks 22 and 23 which are adjustably secured to said ring 1 by the respective screws 25 and 26. As indicated in Fig. III said hook 23 is engaged with the screw 26 by 20 a loop 27 which permits longitudinal adjustment of said hook with respect to said spring 21 to vary the tension of the latter and, consequently, to vary its pressure upon said cams 13. The extent of inward movement of said cams, under pressure of said 25 spring 21, is precisely predetermined by the adjustable stop devices, including the respective plates 28 which may be clamped in adjusted position by the screws 29 which 30 respectively extend through them into engagement with said ring 1. When said screws 29 are loosened, said plates 28 may be turned thereon to overhang said holes 19, more or less, as indicated in Fig. IV, and then be 35 rigidly secured in such adjusted position, by tightening said screws 29. Said plates may be thus variably set, so as to encounter the screws 18 and thus stop the inward movement of said cams 13, at any desired point 40 within the range of movement of said screws 18 in said holes 19.

It is to be understood that said cams 13 remain stationary, under pressure of said spring 21, holding their screws 18 against 45 said plates 28, during the normal operation of the sinker mechanism, with thread free from knots; so as to cast the loops of the thread 31 from the needles 10, in the ordinary way. However, when a knot 32 in 50 said thread is presented at the throat 34 of any sinker 8, such sinker, of course, then encounters more resistance than is afforded by the passage of the smooth thread, and is pressed outwardly so as to permit the passage 55 of said knot by the yielding movement of the cam 13 by which said sinker is being actuated. It is to be noted that the construction and arrangement of said spring 21 is such that very delicate adjustment of the 60 pressure maintaining said cams 13 in the normal position, predetermined by the adjustment of said plates 28, may be effected by stretching said spring more or less, by adjustment of said hook 23.

65 It is to be understood that I do not desire

to limit myself to the precise details of construction and arrangement herein set forth, as it is obvious that various modifications may be made therein without departing from the essential features of my invention 70 as defined in the appended claims.

I claim:—

1. In sinker mechanism, the combination with a sinker ring, having a circumferential slot in a plane at right angles to the axis 75 of said ring; of a double pointed cam rigidly mounted in said ring, arranged to thrust the sinkers outwardly; two single pointed cams mounted to oscillate in said slot, with their points respectively opposite the points of 80 said first cam; pivot screws mounted to turn in said ring and respectively rigidly secured in said oscillatory cams; a spiral tension spring, extending in said slot, in operative relation with both of said oscillatory cams; 85 means connecting said spring with said ring, including terminal hooks connected with the respectively opposite ends of said spring, and screws holding said hooks on said ring; one of said hooks having a loop permitting 90 it to be longitudinally adjusted with respect to the screw which holds it; means arranged to adjustably predetermine the extent of the inward movement of said oscillatory 95 cams, with respect to said ring, including clamping screws engaging said ring, stop plates respectively arranged to turn on said clamping screws, when the latter are loosened, and stop screws respectively rigidly secured in said oscillatory cams and arranged to encounter said stop plates. 100

2. In sinker mechanism, the combination with a sinker ring, having a circumferential slot in a plane at right angles to the axis of said ring; of a cam mounted in said ring, 105 arranged to thrust the sinkers outwardly; two cams mounted to oscillate in said slot, arranged to thrust the sinkers inwardly; pivots in said ring for said oscillatory cams; a spiral tension spring, extending in said 110 slot, in operative relation with both of said oscillatory cams; and means arranged to adjustably predetermine the extent of the inward movement of said oscillatory cams, with respect to said ring, including clamping 115 screws engaging said ring, stop plates respectively arranged to turn on said clamping screws, when the latter are loosened, and stop screws carried by said oscillatory cams and arranged to encounter said stop plates. 120

3. In sinker mechanism, the combination with a sinker ring, having a circumferential slot in a plane at right angles to the axis of said ring; of a cam mounted in said ring, arranged to thrust the sinkers outwardly; a cam mounted to oscillate in said slot, arranged to thrust the sinkers inwardly; a pivot screw mounted to turn in said ring and rigidly secured in said oscillatory cam; a spiral tension spring, extending in said 125 130

- slot, in operative relation with said oscillatory cam; means connecting said spring with said ring, including a terminal hook connected with one end of said spring and 5 adjustably secured to said ring; means arranged to adjustably predetermine the extent of the inward movement of said oscillatory cams, with respect to said ring, including clamping screws engaging said ring, 10 stop plates respectively secured by said clamping screws, and stop screws carried by said oscillatory cams and arranged to encounter said stop plates.
4. In sinker mechanism, the combination 15 with a sinker ring, having a circumferential slot in a plane at right angles to the axis of said ring; of a cam arranged to thrust the sinkers outwardly; two cams mounted to oscillate in said slot, arranged to thrust the 20 sinkers inwardly; pivots in said ring for said oscillatory cams; a single spring, extending in said slot, in operative relation with both of said oscillatory cams; means connecting said spring with said ring, at its opposite 25 ends permitting adjustment of its resilient effect upon said cams; and means arranged to adjustably predetermine the extent of the inward movement of said oscillatory cams, with respect to said ring, including stop 30 plates on said ring, and stop screws carried by said oscillatory cams and arranged to encounter said stop plates.
5. In sinker mechanism, the combination 35 with a sinker support; of a plurality of cams mounted to oscillate with respect to
- said support, and arranged to independently thrust the sinkers toward the needles; a single spring, common to all of said cams, arranged to present all of them in position to effect normal operation of said sinkers 40 with respect to the needles, but capable of permitting said cams to independently yield, away from the needles, to permit knitting knotted thread without breaking it; and, means for adjusting said spring; whereby 45 its resilient effect upon all of said cams may be determined by a single adjustment.
6. In sinker mechanism, the combination with a sinker support; of a plurality of cams mounted to oscillate with respect to 50 said support, and arranged to independently thrust the sinkers toward the needles; a single spring, common to all of said cams, arranged to present all of them in position to effect normal operation of said sinkers 55 with respect to the needles, but capable of permitting said cams to independently yield, away from the needles, to permit knitting knotted thread without breaking it; whereby each of said cams is rendered independently operative in relation to said single 60 spring.

In testimony whereof I have hereunto signed my name at Philadelphia, Pennsylvania, this tenth day of October, 1916.
